(57) **CLAIM**

We claim the ornamental design for the arc producing machine with angled edge, as shown and described.

DESCRIPTION

FIG. 1 is a front-left side perspective view of an arc producing machine, examples of which are a welder or plasma cutter, with angled edge showing our new design. FIG. 2 is a front elevation view of the arc producing machine with angled edge.

FIG. 3 is a back elevation view of the arc producing machine with angled edge.

FIG. 4 is a top plan view of the arc producing machine with angled edge.

FIG. 5 is a bottom plan view of the arc producing machine with angled edge.

FIG. 6 is a left side elevation view of the arc producing machine with angled edge; and,

FIG. 7 is a right side elevation view of the arc producing machine with angled edge.

The broken lines in the figures represent portions of the arc producing machine with angled edge and form no portion of the claimed design.
